US0D1079553S

(12) **United States Design Patent** (10) **Patent No.:** **US D1,079,553 S**
(45) **Date of Patent:** **** Jun. 17, 2025**

(54) **ELECTRIC BICYCLE FRAME**

(71) Applicant: **Sailvan Times Co., Ltd.**, Shenzhen (CN)

(72) Inventors: **Xueqiu Pan**, Shenzhen (CN); **Haixuan Xue**, Shenzhen (CN); **Fudan Deng**, Shenzhen (CN); **Yanxing Yu**, Shenzhen (CN); **Baoya Wang**, Shenzhen (CN)

(73) Assignee: **Sailvan Times Co., Ltd.**, Shenzhen (CN)

(**) Term: **15 Years**

(21) Appl. No.: **29/960,223**

(22) Filed: **Aug. 29, 2024**

Related U.S. Application Data

(62) Division of application No. 35/518,179, filed on Apr. 13, 2023 (U.S. filing date under 35 U.S.C. 384), and having an international filing date of Apr. 13, 2023.

(57) **CLAIM**

The ornamental design for an electric bicycle frame as shown and described.

DESCRIPTION

FIG. 1 is a top, front and left perspective view of an electric bicycle frame showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the figures are for the purpose of illustrating portions of the electric bicycle Frame and form no part of the claimed design.

1 Claim, 7 Drawing Sheets
